UNITED STATES PATENT OFFICE.

JOHN HYLARD, OF ST. KILDA, VICTORIA, AUSTRALIA, ASSIGNOR OF FIVE-EIGHTHS TO EDMUND GEORGE HENRY BINGHAM, OF BROOMWOOD, SEVEN OAKS, COUNTY OF KENT, ENGLAND.

MAGAZINE-GUN.

SPECIFICATION forming part of Letters Patent No. 718,055, dated January 6, 1903.

Application filed November 11, 1901. Serial No. 81,884. (No model.)

To all whom it may concern:

Be it known that I, JOHN HYLARD, a subject of the King of Great Britain and Ireland, residing at 20 Acland street, St. Kilda, near 5 Melbourne, in the State of Victoria, Australia, have invented new and useful Improvements in and Relating to Magazine and like Guns, of which the following is a specification.

This invention relates to improvements in 10 magazine rifles or guns and the like, and has for its object to provide a gun with breech-and-bolt mechanism which is simple in construction and more reliable in action than that hitherto in use.

15 The way in which I carry out my invention is as follows, reference being made to the accompanying drawings, in which—

Figure 1 is a side elevation of the breech portion of a magazine-rifle comprising my invention, showing the bolt in its closed and locked position. This figure also shows the optional safety device and the vertically-slid- 20 able part of the rib or flange along the edge of the opening through the breech, hereinafter referred to. Fig. 2 is a sectional elevation of the breech part of the rifle, showing my improved mechanism, the bolt being in the locked position and the hammer in the position it occupies after firing. Fig. 3 is a simi- 25 lar view to Fig. 2, but shows the bolt turned to the unlocked position and the hammer cocked. Fig. 4 is an elevation of my improved mechanism completely withdrawn from the rifle. Fig. 5 is an elevation of the 30 bolt detached from the rifle, showing in dotted lines the firing-pin in the bolt and the extractor in the bolt-head. Fig. 6 is a rear end view of Fig. 5, showing the rotary latch for locking the bolt-cover or dust-guard, as hereinafter described. This figure also shows the 35 pivoted piece or block on the mainspring, hereinafter referred to. Fig. 7 is a front view of the bolt-head. Fig. 8 is a cross-sectional view through the magazine. Fig. 9 is a plan view of portions of the breech bolt and body, 40 showing the cam-surfaces 160.

The same numbers refer to the same parts in the several figures of the drawings.

The breech-body 1 (on which the mechanism is mounted) and the magazine 2 form one 45 part, which can be readily removed from the

gun for cleaning and repairs, the whole being simply held in place by a couple of screws.

At the rear end of the breech body or plate 1 is an upright piece 3, in which is formed a 55 vertical dovetail-shaped channel or groove 4, (indicated by the dotted line in Figs. 2, 3, 4,) which engages a dovetail-shaped rib on a downward extension 5 of the top strap or plate 6. The upright piece 3, above mentioned, 60 has a longitudinally-projecting arm 7 on its upper end, on which arm are mounted, by means of circular dovetail joints 8 and 9, respectively, two springs 10 and 11, 10 being the main spring and 11 a spring connected 65 to the rear end of a lever 12, fulcrumed at 13, between two wings or side pieces 14 (one only of which is seen in the drawings) on the breech body or plate, said lever 12 extending inside the magazine 2, through the rear end 70 thereof. The end 15 of the lever 12 is connected to the cartridge-carrier plate or follower 16 in the magazine by means of a channel-shaped strap and cross-pin, as shown in Figs. 2, 3, and 8. The trigger-guard 17 is 75 also pivoted at 18 on the breech body or plate 1, and said guard has a projection 19 foreengaging and actuating the spring 11, connected to lever 12, as hereinafter described. The trigger 20 and hammer 21 are also centered, respectively, at 22 and 23 between the 80 above-mentioned wings or side pieces 14 on the breech-body, the trigger-spring being also held between said wings by the pin 18a.

The cartridge-carrier plate or follower 16 is 85 preferably provided with a ridge 24 (see Fig. 8) on one side, so that the cartridges when dropped into the magazine one by one take up their place in a zigzag fashion.

On the main spring 10 I pivotally mount, 90 preferably by means of a circular dovetail joint 25, a block 26. This block is rounded off or inclined at the top on one side, as shown in Fig. 6, and a notch 27 is formed in the rear end of said block for the purpose of engaging the top strap 6 (see Fig. 3) of the breech or its equivalent, as hereinafter described.

28 is the bolt, 29 the firing-pin in said bolt, and 30 the extractor, which latter may be of 95 any well-known or convenient type. A sloping or cam-shaped recess 31 is formed in the

rear end of the bolt 28, in which recess the nose of the hammer 21 works.

32 is the dust guard or cover, provided with longitudinal slots 150, as shown in Fig. 3, 5 which permit it to slide lengthwise into and out of engagement with the fastening-hooks 151, which project from the upper surface of the breech-bolt 28. The hooks 151 project rearwardly, and the dust guard or cover 32 10 of the bolt is locked in position by means of a rotatable latch 33, one end, 34, of which engages with the rear end of said cover, as shown in Fig 6, when the latch is turned to the position to lock the cover.

15 The bolt-head 35 projects laterally and engages with a rib or flange 36 along the edge of the opening through the breech into the magazine, and the rear end of said rib 36 is formed as a vertically or horizontally slidable 20 piece 37, (which may be retained in its normal position by a spring,) so that by depressing 37 a gap may be formed in the rib 36 whereby the bolt-head 35 may be disengaged from said rib and the bolt be completely withdrawn.

25 The top part of the slidable piece 37 normally forms a continuation of the rib 36, and the spring which holds it up is not shown. The piece 37 is pressed down by hand to open and form the gap when desired, and when a spring 30 is provided it rises automatically to close the gap when released. The spring may, however, be omitted and the piece 37 may be raised by hand.

The rear end of the bolt 28 is provided with 35 a downwardly-projecting cam-shaped piece 38, which when the bolt-handle 39 is turned into position for unlocking the bolt engages the before-mentioned pivoted block 26 on the mainspring 10, depresses the mainspring, and 40 cocks the hammer 21 by means of the forward end 10^a of said mainspring, which engages a notch 40 in the hammer and moves it to the cocked position shown in Fig. 3, the forward end of the trigger engaging a projection or shoulder 41 on the hammer and being held in engagement therewith by the limb 42 of the trigger-spring, whose other limb 43 is formed at its lower end 42^a to act as a latch for holding the pivoted trigger-guard 17 in 45 the normal position, as shown in Figs. 2 and 3.

38^a (see Figs. 5 and 6) is a projecting plate or rim-piece on the rear end of the bolt, which acts on the pivoted block 26 on the final movement of the bolt to the locked position.

55 In order that the pivoted block may be operated during the rotary movement of the bolt to the locked position, which follows its forward and longitudinally-sliding movement to close the breech, one or more opposed inclined cam-surfaces 160 are formed on the breech-bolt and on the breech-body, as shown in Figs. 1 and 5, so that a final forward movement is given to the bolt sufficient to operate the block while the bolt is 65 being turned to its final position. As the mainspring 10 is depressed to full-cock ten-

sion the pivoted or oscillating block 26 moves on its pivot, so that the notch 27 in said block engages the top strap 6, and thus automatically locks the mainspring 10 in the tension 70 position, or, in other words, bolts the rifle at safety, so that it is impossible to drop the hammer 21 by pulling the trigger when the bolt 28 is turned to the position for withdrawal. The turning of the bolt to this position also 75 draws the point of the firing-pin 29 into the bolt by means of a sloping or cam surface 44, formed on the bolt-head, working on a sloping surface 45 on the firing-pin. The bolt-head 35, in which is fitted the extractor 30, is 80 screwed into the front end of the bolt.

The magazine cut-off 46 (see Fig. 8) is so arranged that it requires an upward movement to enable it to be moved to cut off the magazine, an upward movement being also 85 required to again open the magazine. This is brought about by providing a rib or projection 47 on the under side of the cut-off, which must be sprung over the edge of the opening into the magazine to enable the cut-off to be 90 moved to open or close the magazine. By this arrangement the liability of accidentally cutting off the magazine is reduced to a minimum.

I also provide an optional safety 48 (see 95 Fig. 1) to my improved rifle, which consists of a slidable wedge 49 or the like, which can be moved into position to engage the forward end of the trigger and prevent its being pulled.

When it is desired to recharge the magazine by loose loading—that is to say, by taking a number of loose cartridges in the hand and dropping or letting them fall into the magazine as rapidly as possible—the pivoted trigger-guard 17 is moved to the position shown in Fig. 4, so that the projection 19 thereon engages the spring 11, connected to lever 12, whose forward end 15 is connected to the cartridge-carrier plate or follower 16 in 105 the magazine, thus raising the rear end of said lever 12 and depressing its forward end, thereby rapidly moving said carrier-plate to the bottom of the magazine and permitting the cartridges to be dropped in, as above mentioned, it being understood, of course, that the bolt has been drawn back to the correct position to open the magazine, or the cartridges may be inserted in the ordinary way, either singly or in clip-packs, without pulling 110 115 down the trigger-guard and lowering the carrier-plate, as above described.

When the bolt 28 is moved forward in the usual way, it moves the topmost cartridge, which was brought into position by the action 125 of spring 11 on lever 12, into its chamber in the barrel, and when the bolt is turned to its locked position, but only at the last extremity of this movement, the before-mentioned pivoted block 26 on the mainspring is moved 130 forward on its pivot 25 so as to disengage its notch 27 from the top strap 6, thus allowing

the mainspring 10 its free action or upward movement to throw the hammer 21 when the trigger is pulled. It will be observed that up to this moment the gun has been locked (automatically) at safety, and accidental turning of the bolt 28 to the position for withdrawal will again automatically put the rifle at safety by depressing the pivoted block 26 so that its notch 27 again engages the top strap 6. On the other hand, should the bolt not be fully turned to its locked position the action of pulling the trigger causes the hammer to act on the cam-shaped recess 31 in the bolt in such a way as to automatically throw the bolt completely home to its fully-locked position.

What I claim is—

1. The combination, with a breech-body, and a stationary top plate 6; of a hammer and a hammer-mainspring supported by the said body, a safety-block 26 pivoted to the said spring and provided with a notch for engaging with the top plate 6, and a slid-
20 able breech-bolt provided with a cam for actuating the block 26, substantially as set forth.

2. The combination, with a breech-body provided with a stationary catch, of a hammer and a hammer-mainspring supported by the said body, a safety-block pivoted to the said spring and engaging with the said catch when moved downward and rearward, and a slid-
25 able breech-bolt provided with a cam 38 for depressing the said block, and having a plate for moving the said block forward out of engagement with the said catch, said breech-bolt and breech-body having also inclined op-
30 posed surfaces 160, substantially as set forth.

In testimony whereof I have signed my name to this specification in the presence of the subscribing witnesses.

JOHN HYLARD.
